UNITED STATES PATENT OFFICE.

JOHN S. WAGNER, OF RED WING, MINNESOTA.

RAIL-Straightening Device.

1,077,019.

Specification of Letters Patent.

Patented Oct. 28, 1913.

Application filed April 14, 1913. Serial No. 761,013.

To all whom it may concern:

Be it known that I, JOHN S. WAGNER, a citizen of the United States, residing at Red Wing, in the county of Goodhue and State 5 of Minnesota, have invented certain new and useful Improvements in Rail-Straightening Devices; and I do declare the following to be a full, clear, and exact description of the invention, such as will enable others skilled 10 in the art to which it appertains to make and use the same.

This invention relates to improvements in rail straightening devices and particularly to the devices for straightening the switch 15 points of railway rails.

One object of the invention is to provide a device of this character by the use of which a bent switch point may be quickly and easily straightened by one man without 20 taking the parts up or removing any bolts or spikes.

Another object is to provide a device of this character which will be simple, strong, durable and inexpensive in construction, efficient and reliable in operation and well adapted to the purpose for which it is designed.

With these and other objects in view, the invention consists of certain novel features 30 of construction, and the combination and arrangement of parts as will be more fully described and claimed.

In the accompanying drawings: Figure 1 is a perspective view of a portion of a rail- 35 way rail and a bent switch point showing the application of the invention for straightening the point. Fig. 2 is a side view of one side of the device with parts broken away and in section; Fig. 3 is a side view 40 of the opposite side thereof; Fig. 4 is a top plan view of the device; Fig. 5 is an outer end view thereof; Fig. 6 is an enlarged vertical cross sectional view taken on the line 6-6 of Fig. 3; Fig. 7 is a detail perspective 45 view of the movable or point engaging member of the device looking toward one side thereof; Fig. 8 is a similar view looking toward the other side of said movable member; Fig. 9 is a detail perspective view of the 50 segmental gear for operating the movable or point engaging member of the device.

My improved rail or switch point straightening device comprises a stationary or anchoring member 1 comprising a rail 55 engaging hook 2 having on its inner end parallel outwardly and downwardly extend-

ing guide plates 3 in the inner sides of which and in a plane below the inner end of the hook 2 are formed alined longitudinally disposed guide grooves 4. In one of 60 the guide plates 3 and communicating with the groove 4 in said plate is a threaded aperture 5 in which is arranged a stop screw 6.

Slidably mounted between the lower portion of the guide plates 3 is a movable or 65 switch point engaging member 7 comprising a block having on its side edges longitudinally disposed tongues 8 which enter and have a sliding engagement with the 70 grooves 4 in the inner sides of the plates 3 whereby said block or movable member 7 is 75 slidably supported in the stationary or anchoring member. The tongue 8 on one side of the block is recessed or cut away for a portion of its length to form a space 9 with 80 which the inner end of the stop screw 6 is engaged, said screw thereby limiting the 85 sliding movement of the member 7 in either direction. In the inner end of the block or member 7 is formed a notch 10 the upper 80 wall of which is beveled and overhangs or projects beyond the end of the lower wall of the notch as shown at 11, or in other words the notched inner end of the block 7 90 conforms to the shape of the flange of the 85 switch point with which said inner end of the block is adapted to be engaged. The adjacent ends or lower corners of the guide plates 3 of the stationary member of the device are preferably cut off at an angle as 90 shown at 12, thus preventing said corners from interfering with the further engagement of the movable member of the device with the switch point.

On the upper side of the movable member 95 or block 7 of the device is formed a toothed rack 13 with which is adapted to be engaged a segmental gear 14 which is mounted on a short shaft 15 the ends of which are engaged with the guide plates 3 on the stationary member of the device as shown. On the gear 14 is formed a shank 16 having therein a socket 17 with which is adapted to be engaged a lever 18 whereby the gear 14 may be rocked or oscillated on the shaft 15 and the teeth of the gear thus engaged with the teeth of the rack 13 on the movable member 7 whereby the latter is projected and retracted as will be readily understood. The lever 18 preferably has a detachable engagement with the socket 17 in the shank 16 of the gear and the outer end of said lever 18 105 110

preferably has formed thereon a tapered outer end 19 whereby the lever may be employed for other purposes when disengaged from the socket in the shank 16 of the gear.

- 5 In the operation of my improved switch point straightening device a wedge or stop block 20, which may be of any suitable construction, is placed between the switch point and the adjacent side of the rail opposite the bend in the point or at any other desired position after which the hook 2 of the stationary or anchoring member of the device is engaged with the rail or other fixed object and the notched end of the movable member or block 7 of the device is engaged with the flange of the switch point or other part to be straightened and at a suitable distance from the bend therein as clearly shown in Fig. 1 of the drawings.
- 10 When the parts have thus been arranged and adjusted the lever 18 is swung outwardly thereby rocking the gear 14 in the proper direction for projecting or forcing the movable member 7 inwardly which operation will straighten or remove the bend from the switch point.
- 15
- 20
- 25

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

In a rail straightening device of the character described the combination of a semi-circular rail gripping member, guide plates arranged in parallel relation on the inner end of said member, the former having therein oppositely disposed longitudinal grooves, a wedge slidably mounted between said plates and having a shoulder formed at its outer end, the latter being adapted to fit the part with which said wedge is engaged, longitudinal tongues formed on the sides of said wedge and adapted to engage the grooves in said guide plates, the tongue on one side of said wedge being broken away to form a recess, a stop screw arranged in one of said guide plates and adapted to project within said recess to limit the movement of said wedge, a rack arranged on said wedge, a segmental gear pivotally mounted between said plates in a position to engage said rack, a shank formed on said gear having therein a socket and an operating lever adapted to detachably engage the socket in said shank whereby said gear may be manually operated to project and retract said wedge.

In testimony whereof I have hereunto set my hand in presence of two subscribing witnesses.

JOHN S. WAGNER.
